DESIGN FOR A COMBINED ELECTRIC SWITCH AND RHEOSTAT

Ray R. Hutcheson, Brooklyn, N. Y.

Application October 4, 1946, Serial No. 133,764

Term of patent 14 years

(Cl. D26—13)

To all whom it may concern:

Be it known that I, Ray R. Hutcheson, a citizen of the United States, residing at Brooklyn, in the county of Kings and State of New York, have invented a new, original, and ornamental Design for a Combined Electric Switch and Rheostat, of which the following is a specification, reference being had to the accompanying drawing, forming a part thereof, wherein:

Fig. 1 is a plan view of a combined electric switch and rheostat showing my new design;

Fig. 2 is an end view thereof;

Fig. 3 is a side elevation thereof; and

Fig. 4 is a bottom plan view thereof.

I claim:

The ornamental design for a combined electric switch and rheostat, substantially as shown.

RAY R. HUTCHESON.
